UNITED STATES PATENT OFFICE.

ABBOTT L. COMBES AND HARRY M. KEYSER, OF EAST FALLS CHURCH, VIRGINIA.

RIPPING UNIT FOR METAL CANS.

Refiled for abandoned application Serial No. 748,718, filed November 8, 1924. This application filed June 8, 1926, Serial No. 114,575.

This invention relates to an improved ripping unit for metal cans of the character commonly employed in canning food-stuffs or the like and seeks, among other objects, to 5 provide a novel means whereby a ripping element for opening such cans may be feasibly enclosed therein.

As is well known, the ordinary metal can of the kind indicated is not provided with 10 any self-contained means whereby the can may be readily opened. Consequently, it is always necessary, in order to open such a can, to have at hand some kind of a can opener. If the can opener becomes lost or 15 misplaced, as very often happens, quite a difficult situation is presented and not infrequently the can remains unopened. The present invention, therefore, further seeks to obviate these difficulties by providing each 20 can with a ripping element and wherein the ripping element will be equipped with a key which, to all intents and purposes, will be permanently attached to said element so that the key will be always ready at hand for 25 manual manipulation to open the can, thereby avoiding the necessity for the use of a can opener as well as obviating possible failure in getting the can open.

The invention seeks as a further object 30 to provide a device wherein the ripping element will be so mounted in the can that less strength and skill will be required to open the can than with an ordinary can opener.

The invention further seeks to provide a 35 device which may be produced and sold as an entirely distinct article of manufacture.

A further object of the invention is to provide a device which will necessitate practically no structural change in the usual 40 can.

And the invention seeks, as a still further object, to provide a device which will be simple, inexpensive, and efficient.

Other objects of the invention not specifically mentioned in the foregoing will appear during the course of the following description.

The present application is a substitute for the applicants' abandoned application filed 50 November 8, 1924, Serial No. 748,718.

In the accompanying drawings:

Figure 1 is a fragmentary perspective view showing the improved ripping unit installed in a conventional metal can, parts 55 being broken away and illustrated in section.

Figure 2 is a detail perspective view of the unit, partly broken away and shown in section.

Figure 3 is a view similar to Figure 1, but showing a slight modification of the invention.

Before proceeding with a description of the present invention, it may be stated that we are well aware that it has been heretofore attempted, in various ways, to embody a ripping unit or element in metal cans for containing foodstuffs. However, in so far as we are aware, such attempts have in the great majority, proven totally unsuccessful while practically all have been ultimately 70 abandoned. This has been due to many reasons, the outstanding of which are that, due to peculiarity of can structure, the ripping wire could not be successfully introduced by machinery, while in other cases, 75 the increased cost of manufacture has been prohibitive. The present invention has, therefore, been developed with a view of overcoming and avoiding these various difficulties. 80

Referring now more particularly to Figures 1 and 2 of the drawings, we employ a carrier ring 10 which may be of suitable sheet metal and may be endless, although in the present instance, we have shown said ring 85 split. Secured upon the ring is a ripping element 11 preferably of wire and, as will be observed, the ring is rolled inwardly at its lower edge to define a channel 12 seating the ripping element. A flange 13 is thus produced, which flange extends partially over the ripping element so that while a creeping longitudinally flexing movement of said element will serve to draw the element upwardly through the mouth of the channel, 90 the ripping element is, nevertheless, firmly connected with the carrier ring. At one end, the element 11 is formed with a down-turned anchoring hook 14 engaging the flange 13 at one end of the carrier ring while 100 at the opposite end of said ring, said element is bent up at a point close to the opposite end of said flange to provide a free terminal 15.

In Figure 1 of the drawings, the unit is 105 shown installed in a conventional metal can 16 having a lid 17 countersunk in the upper end of the can. The lid is provided with the usual rim flange 18 crimped about a flange 19 on the side wall of the can to form 110

a closed joint between the lid and can. As will be understood, all of this structure is in accordance with conventional practice. Before the lid is applied, the ripping unit of the present invention is slipped around the base of the flange 18 so that the carrier ring 10 lies flat thereagainst while the terminal 15 of the element 11 is coincidently inserted through a suitable opening in the lid. The lid 17, with the ripping unit thereon, is then pressed into the upper end of the can and the can crimped in the usual manner, as shown, for connecting the lid with the can. The terminal 15 of the ripping element 11 is then bent inwardly away from the periphery of the lid, preferably in the manner illustrated in Figure 1, and equipped with a key 20. This key may be struck from suitable sheet metal and formed therefrom is a loop 21 through which the terminal 15 is inserted and bent to form a hook 22 connecting the key with said terminal. Thus, the key is, to all intents and purposes, permanently attached to the free end of the ripping element and lies flat against the top wall of the can in a position out of the way. The joint between the terminal 15 and the top wall of the can is then finally sealed with solder for hermetically closing the can.

Attention is now directed to the fact that the crimping operation incident to the application of the lid 17 produces an out-turned annular lip or flange 23 at the upper edge of the carrier ring 10 which lip is seated against the upper edge of the side wall of the can and is clamped by the flange 18 of the lid. Further, the carrier ring is tightly confined between the base of said flange and the side wall of the can while the lid bears against the top of the flange 13. The device is thus firmly held in position and limited against displacement in any direction. Accordingly, the ripping element 11 will always be supported immediately beneath the lid so that by grasping the key and turning said element thereon, the element will be drawn from the channel 12 of the carrier ring and caused to rip the lid along the line of a circle close to the side wall of the can. The can may accordingly be opened with facility.

In Figure 3 of the drawings, we have illustrated a slight modification of the invention wherein the carrier ring, indicated at 10', is rolled outwardly at its lower edge to define a channel 24 in which is mounted a ripping element 25 like the element 11 of

Figs. 1 and 2. Accordingly, when the device is, in the manner previously indicated, inserted in a can, as conventionally illustrated at 26, the mouth of the channel faces the side wall of the can. The free terminal 27 of the element 25 is, therefore, brought through said side wall preferably at the upper end of the seam therein and equipped with a key 28. This key is substantially identical with the key 20 of Figure 1, but is bowed transversely to seat flat against the side wall of the can. Thus, when the key is turned to wind the element 25 thereon, the side wall of the can will be ripped by said element around the circumference of the can. Otherwise, this modified structure is identical with the preferred form of the invention and further description is accordingly believed unnecessary. However, it should be stated that while we have illustrated and described the present invention in connection with a cylindrical can, still, it is recognized that while most of the cans used in canning food-stuffs or the like are of such shape, cans of other shapes are employed. In any such instance, the carrier ring of the ripping unit will be shaped accordingly to fit within the can in the manner previously indicated and the term "carrier ring" as herein used shall, therefore, be construed to comprehend such variations in shape.

Having thus described the invention, what we claim is:

The combination with a can body, and a lid crimped upon the can body, the lid being provided with a sunken portion extending into the can body and including a wall at the bottom of said sunken portion, of a carrier ring embracing said sunken portion and initially inserted into the can body with said sunken portion, the outer margin of said ring being interfolded in said crimp for securing the ring within the can body as the lid is secured to said body, the inner margin of said ring being bent to form a channel providing a stop disposed to abut said wall of the lid for initially locating the ring on the lid, and a ripping element held in said channel and operable to rip a wall of the can, said ring and element providing a separate ripping unit.

In testimony whereof we affix our signatures.

ABBOTT L. COMBES.
HARRY M. KEYSER.
